ORTHODONTIC WATER FILLED GUM SOOTHER AND PACIFIER

Stephen B. Sofro, Providence, R.I., assignor to Reliance
Products Corporation, Woonsocket, R.I.

Filed Apr. 20, 1972, Ser. No. 246,115

Term of patent 14 years

Int. Cl. D24—05

U.S. Cl. D83—8 C

FIG. 1

FIG. 2

FIG. 3

FIG. 4

FIG. 5

FIG. 1 is a front elevation of an orthodontic water filled gum soother and pacifier embodying my new design;

FIG. 2 is a rear view thereof;

FIG. 3 is a side view thereof;

FIG. 4 is a top plan view thereof; and

FIG. 5 is a bottom plan view thereof.

I claim:

The ornamental design for an orthodontic water filled gum soother and pacifier, as shown.
